UNITED STATES PATENT OFFICE.

CHARLES ALLEN SNYDER, OF DUBUQUE, IOWA.

SAFETY DEVICE FOR RAILROAD-CROSSINGS.

1,342,002.

Specification of Letters Patent. Patented June 1, 1920.

Application filed January 24, 1917. Serial No. 144,228.

To all whom it may concern:

Be it known that I, CHARLES ALLEN SNYDER, a citizen of the United States, and resident of Dubuque, in the county of Dubuque, and in the State of Iowa, have invented a certain new and useful Improvement in Safety Devices for Railroad-Crossings, and do hereby declare that the following is a full, clear, and exact description thereof.

The object of my invention is to prevent collisions, or accidents at railroad crossings by means that will combine the qualities of simplicity, economy and efficiency, and broadly stated my invention achieves these objects by so constructing the road, or street at or near the railroad tracks as to compel approaching vehicles to travel at a slow speed sufficiently near the track as to enable instant stoppage, or a change of direction which will avoid coming on to the track.

In the accompanying drawings—

Figure 1 is a top plan view showing one embodiment of my invention;

Fig. 2 is a similar view showing a different form, or shape of the speed controlling device;

Fig. 3 is a top plan view showing still another form.

Referring to the drawing, 10 designates a portion of railroad track and 11 a roadway, or street crossing the same. On each side of the track at, or near the same, an obstruction 12 is provided in the roadway preventing a direct approach to the railroad track, to pass which the roadway is branched to provide on each side of the obstruction a sharply bent, or curved laterally extending passage-way 13. The obstruction 12 is preferably in the form of a mound which may be wholly, or partially surrounded and protected by an abutment, or curb 14 of stone, or concrete, and of such height as to make impossible the traverse, or passage over the mound of approaching vehicles, so that the latter perforce are compelled to change their direction and at sufficiently sharp angle as to compel a reduction of speed, if at the time of approach the car, or vehicle is moving at a speed that will be dangerous immediately at or near the railroad tracks.

Situated on the mound, or obstruction, and preferably at the point, or side nearest

the approaching vehicle, is a warning sign-post 15, which may be the kind ordinarily, or commonly used at railroad crossings.

The obstruction, or mound, and the road branches about it may be angular, as shown in Figs. 1 and 2, or round, or elliptical, as shown in Fig. 3, the form being such as may be dictated by matters of appearance, or design, or the local conditions, or requirements as to the reduction of speed.

The angular arrangement shown in Fig. 2, where the turns are at right angles, obviously would be more effective than the angular arrangement shown in Fig. 1, where the turns are not so abrupt, or sharp.

If desired, as shown in Fig. 1, at the angles or turns midway of each branch, there may be a guard 16 in the form of a short wall, or fence.

By branching the road, or causing it to pass around the obstruction on both sides, not only is collision of vehicles approaching each other avoided, but should a vehicle pass around the obstruction and be moving at a speed by the time it goes around the obstruction that would make it difficult to stop to avoid a collision with a passing train, such vehicle could continue on about the obstruction and double upon itself. An important advantage in compelling a change of direction of a vehicle at, or near the railroad track, is that the driver has a better command, or view of the railroad track in the direction from which approaching trains are coming, such view being first down along the track in one direction as he enters the branch, and then as he makes the turn in the branch to reenter the main road he commands a view of the railroad track in the opposite direction. The device in itself is a warning, or notice of nearness to a railroad track so that a driver before he reaches the device upon seeing it knows that he is approaching a railroad crossing so that its efficiency is two-fold, for it acts as a signal, or warning, and should its warning effect be disregarded, then it compels running the vehicle at a speed which will prevent collision, or accident on the railroad track.

The cost of construction and maintenance is practically nothing more than that of ordinary road construction; and the device affords opportunity for, or is an ornamentation, or enhancement of the appearance of the surroundings.

110

Having thus described my invention what I claim is—

1. A railroad crossing having in the road, or street at or near the track an obstruction, and devious passage-ways connecting portions of the road, or street on both sides of said obstruction, the opposite sides of said obstruction being symmetrical, and each formed on converging lines.
10. 2. A railroad crossing having in the road,

or street at or near the track an obstruction, and devious passage-ways connecting portions of the road, or street on both sides of said obstruction, said obstruction being in the form of a mound of substantial area 15 with sides that extend first transversely outward and finally transversely inward.

In testimony that I claim the foregoing I have hereunto set my hand.

CHARLES ALLEN SNYDER.
